UNITED STATES PATENT OFFICE.

FRANK B. HUSK, OF DANBURY, CONNECTICUT, ASSIGNOR TO MORLOCK AND HUSK, OF DANBURY, CONNECTICUT, A COPARTNERSHIP.

MACHINE FOR POUNCING HAT-BRIMS.

No. 808,373.

Specification of Letters Patent.

Patented Dec. 26, 1905.

Application filed April 27, 1905. Serial No. 257,577.

To all whom it may concern:

Be it known that I, FRANK B. HUSK, a citizen of the United States, residing at Danbury, county of Fairfield, State of Connecticut, have invented a new and useful Machine for Pounding Hat-Brim, of which the following is a specification.

My invention has for its object to provide a light, simple, durable, and inexpensive machine for pounding both sides of the brims of hats, more especially of felt hats.

With these ends in view I have devised the novel hat-pounding machine which I will now describe, referring to the accompanying drawings, forming a part of this specification, and using reference characters to indicate the several parts.

Figure 1 is a plan view of the machine complete; Fig. 2, an elevation of the feeding mechanism detached; Fig. 3, a side elevation of the machine with the feeding mechanism removed; and Fig. 4 is an elevation as seen from the right in Fig. 3, showing the pad-carriers at the extreme of their outward movement.

10 denotes the base-plate of the machine, which may rest upon a suitable standard or on a bench, as preferred. Power is applied to drive the machine by means of a belt (not shown) passing over a belt-pulley 11 on a shaft 14, which is journaled in a bracket 13, rigidly secured to the base-plate and extending outward and upward therefrom, and in a bearing 15 on a standard 16, also secured to the base-plate.

17 denotes a clutch the operation of which is to connect and disconnect the shaft and the belt-pulley in use. This clutch is operated by means of a hand-lever 18, the operative end 40 of which lies in position to be readily grasped by the operator in use.

At the inner end of the shaft is a gear-wheel 19 and a miter-pinion 20, rigidly secured together. The feeding mechanism, 45 which is driven from the miter-pinion, comprises the usual conical feed-rollers 21 and 22, carried by oblique shafts 23 and 24, journaled in boxes secured to a standard 25, itself rigidly secured to and extending upward from 50 the base-plate. The boxes in which one of these shafts, in the present instance shaft 24, is journaled are fixed to the standard. The inner end of this shaft is provided with a miter gear-wheel 26, which meshes with the mi-

ter-pinion on the main shaft. Shafts 23 and 24 are provided with corresponding miter gear-wheels 27, engaging each other, by which power is transmitted from one to the other. The box 28, in which the inner end of shaft 23 is journaled, is pivoted to standard 25, so 60 so as to oscillate thereon in the vertical plane. The box 29, in which the outer end of this shaft is journaled, is carried by a pin 30, which slides in an arc-shaped slot 31 in the standard, a spring 32 acting to force box 29 65 downward and press the feed-roller carried thereby toward the companion feed-roller.

33 and 34 denote, respectively, the upper and lower pad-carriers, each of which is provided with a slot 35 at right angles to its path 70 of movement and carries a pad 36, to which sheets of sandpaper (not shown) are secured in use. The lower pad-carrier 34 is pivoted to a vertical plate 37, as at 38. Plate 37 may be cast integral with or rigidly secured to a 75 standard 41, which is itself rigidly secured to the base-plate. The upper pad-carrier 33 is pivoted on a pin 39, extending from a slide 40, which moves in vertical ways 42 in plate 37.

43 denotes shafts journaled in bearings 44 80 in standard 41. At the inner ends of these shafts are pinions 45, which mesh with gear-wheel 19 on the main shaft, and at their outer ends are disks 46, which lie in countersunk recesses 47 in the outer face of plate 37. Each 85 of these disks is provided with a pin 48, which extends eccentrically from the outer face thereof. 49 denotes blocks pivoted on these pins and adapted to slide in slots 35 in the pad-carriers. It will thus be seen that when 90 the machine is in use rotation of shafts 43 will cause the blocks to reciprocate in the slots in the pad-carriers and will cause the pad-carriers themselves to reciprocate in opposite directions, owing to the fact that the 95 blocks and pins are oppositely adjusted relative to the pad-carriers, as clearly shown in Fig. 4. Starting with the pad-carriers in the position shown in Fig. 4 each rotation of the disks will cause the pad-carriers to swing to 100 the extreme of their movement in opposite directions and to instantly return to the sliding position. The pad-carriers remain stationary but an instant at each extreme of their movement, the return movement commencing at once, so that the least possible time is lost, and the pounding of both sides of the hat-brim is effected very quickly, owing 105

to the rapid movement and quick return of the pad-carriers. An adjustable pressure is maintained upon the upper pad-carrier by means of a weight 50, which slides on an arm 51, pivoted to a bracket 52, extending upward from standard 41. The outer end of arm 51 lies in a notch 53 in the top of slide 40, which prevents any lateral movement of the arm and weight. The hats while being acted upon are held inverted—that is, with the crowns downward—and are retained in position while the brims are between the pouncing-pads by means of a pin 54, which passes into the crowns from above. This pin is adjustably secured in a bracket 55, which is rigidly secured to and depends from the pin 39, on which upper pad-carrier 33 is pivoted.

The upper pad-carrier and upper feed-roller may be lifted simultaneously to permit the insertion or removal of a hat by means of a hand-lever 56, pivoted to a bracket 57 on the base-plate. This lever carries a roller 64, which engages the under side of a curved lever 58, pivoted to a bracket 59 on the base-plate.

60 denotes a link one end of which is pivoted to the free end of lever 58 and the other to an arm 61, which is rigidly secured to slide 40.

62 denotes a lever one end of which is pivoted to the standard 25, which carries the feeding mechanism and which extends under upper feed-roller shaft 23, and the other end of which is pivoted to link 60, as at 63.

Lever 58 is so shaped that in the normal or operative position of the parts roller 64 on hand-lever 56 bears against a downwardly extending incline. When this hand-lever is swung from the position shown in Fig. 3 toward the right, the free end of lever 58 will be raised, and with it the link, arm 61, and lever 62, which will carry with them both the upper pad-carrier and the upper feed-roller and will permit the operator to insert or remove a hat.

The operation of the machine as a whole will be readily understood from the description already given. In brief, the operator by means of hand-lever 56 raises the upper pad-carrier and upper feed-roller, places the brim of a hat to be pounced upon the lower feed-roller and the lower pad-carrier, then lowers the upper feed-roller and upper pad-carrier to place, pin 54 passing within the crown of the hat, which is held downward, and then the operator by means of hand-lever 18 operates the clutch to connect the shaft with the belt-pulley. The feed-rollers at once commence to carry the brim of the hat forward, both sides of which are subjected to the action of pouncing-pads faced with sandpaper upon the pad-carriers. The hat while being pounced is retained in position so that it cannot pass out from between the pouncing-pads by means of pin 54.

When the machine is in use, the operator is

simply required to stop and start it and to insert the hats and remove them when pounced, the feeding forward of the hat-brim and the pouncing action being wholly automatic.

Having thus described my invention, I claim—

1. In a machine of the character described the combination with pad-carriers having slots at right angles to their path of movement, of blocks in said slots and rotating disks having pins extending from their faces on which the blocks are pivoted, whereby reciprocatory movement in opposite directions is imparted to the pad-carriers.

2. In a machine of the character described the combination with a lower pad-carrier pivoted to a fixed portion of the machine, an upper pad-carrier and a vertical slide to which the upper pad-carrier is pivoted, of means for reciprocating said pad-carriers in opposite directions and means for raising the slide to lift the pad-carrier carried thereby out of operative position.

3. In a machine of the character described the combination with a slotted lower pad-carrier pivoted to a fixed portion of the machine a slotted upper pad-carrier and a vertical slide to which the upper pad-carrier is pivoted, of blocks adapted to reciprocate in the slots, disks having pins extending from their faces on which the blocks are pivoted, and means for rotating said disks to impart reciprocatory movement in opposite directions to the pad-carriers.

4. In a machine of the character described the combination with a slotted lower pad-carrier pivoted to a fixed portion of the machine a slotted upper pad-carrier and a vertical slide to which the upper pad-carrier is pivoted, of blocks adapted to reciprocate in the slots, disks having pins extending from their faces on which the blocks are pivoted, means for rotating said disks and means for raising the slide and upper pad-carrier out of operative position.

5. In a machine of the character described the combination with a slotted lower pad-carrier pivoted to a fixed portion of the machine a slotted upper pad-carrier and a vertical slide to which the upper pad-carrier is pivoted, of blocks adapted to reciprocate in the slots, rotating disks having pins extending from their faces on which the blocks are pivoted, a pivoted arm engaging the top of the slide and a weight on said arm whereby the upper pad-carrier is retained in operative position in use.

6. In a machine of the character described the combination with a slotted pad-carrier pivoted to a fixed portion of the machine, a vertical slide, a corresponding slotted pad-carrier pivoted to said slide, a bracket secured to said slide and a pin depending therefrom and adapted to enter the crown of a hat to retain the brim in position to be operated.

upon, of blocks adapted to reciprocate in the slots and rotating disks having pins extending from their faces on which the blocks are pivoted.

- 5 7. In a machine of the character described the combination with oppositely-reciprocating pad-carriers and a vertical slide to which one of said pad-carriers is pivoted, of an arm extending from said slide, a link pivoted to
10 said arm, a curved lever to which said link is pivoted and a hand-lever engaging said curved lever by which the slide may be lifted to move the pad-carrier pivoted thereto out of operative position.
- 15 8. In a machine of the character described the combination with oppositely-reciprocat-

ing pad-carriers, a vertical slide to which one of said pad-carriers is pivoted, and feed-rollers one of which is vertically movable, of an arm extending from the slide, a link pivoted to said arm, a lever pivoted to said link and engaging the shaft of the movable feed-roller a curved lever to which the link is pivoted and a hand-lever engaging the curved lever by which the slide, upper pad-carrier and upper feed-roller may be raised.

In testimony whereof I affix my signature in presence of two witnesses.
